Attorney

UNITED STATES PATENT OFFICE.

WALTER R. CLARK, OF BRIDGEPORT, CONNECTICUT, ASSIGNOR TO BRIDGEPORT BRASS COMPANY, OF BRIDGEPORT, CONNECTICUT, A CORPORATION OF CONNECTICUT.

MANUFACTURE OF ELECTRIC-FURNACE LININGS.

Original application filed August 6, 1917, Serial No. 184,675. Divided and this application filed September 8, 1919. Serial No. 322,556.

To all whom it may concern:

Be it known that I, WALTER R. CLARK, a citizen of the United States, residing in Bridgeport, in the county of Fairfield and 5 State of Connecticut, have invented certain new and useful Improvements in Manufacture of Electric-Furnace Linings, of which the following is a full, clear, and exact description.

10 This invention relates to the manufacture of electric furnace linings and the case is a division of my application Serial No. 184,675, filed August 6, 1917.

The invention has particular reference to 15 the manufacture of induction furnaces of the type in which a channel or passage of closed cross-section, communicating with the hearth or chamber at two points, receives a portion of the molten bath, which 20 acts as the secondary of the transformer. The channel or passage through which the metal of the secondary flows is usually formed of or lined with a suitable refractory insulating material, which will satisfactorily withstand the high temperature 25 developed in the operation of the furnace.

One of the primary objects of the present invention is to overcome the disadvantages 30 incidental to the employment of a solid metal templet or pattern, such as has been used in the construction of furnaces of this character. These solid metal templets have in some cases been constructed wholly of brass where the furnace was designed for 35 the melting of brass scrap or the like, and it has been customary to leave the pattern or templet in place in a secondary passage after the latter has been formed by tamping the refractory material about the templet or 40 pattern, the latter being utilized when the completed furnace is first placed in operation. Where such a solid brass templet is used, however, certain drawbacks arise from the expansion which is incident to heating 45 the templet to the melting point, which expansion is considerable and is apt to crack, fissure or otherwise injure the lining of the secondary passage, that usually has a different coefficient of expansion.

50 The primary object of my present invention is to obviate this disadvantage and to facilitate the manufacture of induction furnaces of the type above described.

Another object of the invention is to fur-

nish an improved form of templet or form 55 for use in such manufacture. My improved templet, which can be very readily constructed, neither injuriously affects the lining of the furnace, nor the metal or alloys which are melted in the furnace. The templet is sufficiently hard and strong at ordinary temperatures, however, to enable the refractory material to be tamped or rammed about it in a very convenient and satisfactory manner. 60

To these and other ends, the invention 65 consists in the novel features and procedure hereinafter described and claimed.

In the accompanying drawing:

Fig. 1 is a vertical central section of an 70 induction furnace, showing my improved templet in position in the secondary channel.

Fig. 2 is a section on line 2--2 of Fig. 1.

Fig. 3 is a detail of the templet.

Fig. 4 is an enlarged cross-section taken 75 through one leg of the templet; and

Fig. 5 is a similar section taken through the leg of the templet of somewhat modified character.

In the drawing, I have shown an electric 80 induction furnace having a body 10 composed of a metal jacket or casing 11, and a refractory lining 14. The furnace has a basin or hearth 13 at the upper part, which in this case is formed in a layer or body of refractory material packed within a layer 12 of suitable heat insulating material, such for example as infusorial earth. The layer 14 advantageously consists of a suitable asbestos cement, although I do not limit myself in this respect. The hearth has a pouring spout 15 and a charging opening 16, having a door 17. Beneath the hearth of the furnace shown herein is a closed channel of approximately V-shape, indicated at 18, having substantially straight side portions communicating with each other at an acute angle, as shown at 19, and connecting with the hearth at opposite sides of the latter, as shown at 20. The metal which is received in the channel 18 in the operation of the furnace acts as a secondary of a transformer whose primary is constituted by a horizontally arranged core 21 extending about the upper portion of the channel 18 and having a winding 21^a suitably connected with a source of current. Owing to the arrangement of the two legs of the chan-

nel 18 at an acute angle to each other, the action of the primary is such as to set up a thorough circulation of molten metal in the channel and the bath or pool in the hearth, 5 it being understood, of course, that in practice the upper ends of the continuous channel are in constant communication with the lower part of the hearth which is filled to approximately the level of the pouring spout 10 with a bath of molten metal.

In constructing the lower portion of a furnace such as that selected for illustration, I use a pattern, templet or form 22 for the construction of the channel 18 in 15 the refractory material. In this instance, the templet, which is of the same shape as the passage or channel which it is desired to form, consists of a hollow body or tube 23 of brass, copper, or other suitable metal 20 having an interior filling 24. In the example shown in Figs. 1 to 4, the filling consists of so-called paraffin wax or like hydrocarbon. The templet is held in position in a suitable frame, and the refractory material, such as 25 asbestos cement, in which the secondary channel is to be formed, is tamped or rammed about the templet. The latter is sufficiently hard and strong at ordinary temperatures to allow the refractory material 30 to be firmly packed or rammed around it, so as to obtain a channel of uniform cross-section having a smooth homogeneous surface. The interior filling 24 of the templet is hard enough at ordinary temperatures to 35 afford a very firm and substantial backing for the wall of the relatively thin tube, whereby the collapse of such tube is prevented. After the ramming operation has been completed, the furnace structure is then 40 dried. It may be dried in a suitable oven or kiln, for example, and when so dried, the heat melts the wax and causes it to flow out of the ends of the templet tube. Or, if desired, an electric current can be passed 45 through the tube from an exterior source, or current can be induced in the tube by the use of the transformer for the purpose of melting and eliminating the templet core or filling. If the filling is eliminated electrically, the ends of the tube may be connected to the poles of an exterior source of current, or the transformer may be utilized 50 if the ends of the tube are suitably interconnected so as to provide a closed circuit. 55 After melting out the wax or other filler, the circulation of the current in the tube may be continued for the purpose of drying out the lining of the passage.

In starting the furnace, molten metal is 60 poured into the furnace chamber and the same completes the secondary in an obvious manner. The tubular metallic remnant of the templet remaining in the furnace is preferably melted before additional metal is 65 poured in, and in melting the tube (by

means of the transformer) there is no deleterious effect upon the lining, owing to the fact that the tube is then free to collapse in an inward direction. In other words, there will be no injurious pressure exerted 70 by the tube in an outward or lateral direction as a result of the expansion incidental to the heating of the tube to the melting point. The tube can advantageously be made of copper, so as to provide for a maximum expansion or the extension of the same without rupture and at the same time owing 75 to the character of the templet, such expansion or extension will not injure the lining. If brass is to be melted in the furnace, moreover, the copper will alloy itself readily with the charge. 80

In the modification shown in Fig. 5, the templet consists of the comparatively thin metal tube 23 similar to that previously described, with a filling 25 of sand, which is another material that reinforces the templet interiorly to such an extent as to offer sufficient resistance in ramming. When the operation of ramming has been 90 completed, the sand can be run out of the tube very readily by turning it upside down, as will be understood. The tubular metal portion of the templet is then free to collapse inwardly so that the metal there- 95 of, in expanding under the application of heat, will not exert injurious pressure on the lining of the secondary passage.

Various changes may be made in the details of the procedure, and in the templet 100 or form, without departing from the scope of my invention, as set forth in the claims.

I do not claim broadly herein the method of making the refractory structure of an electric induction furnace having a passage 105 of closed cross-section arranged beneath and in communication with the hearth or basin, thereof, which comprises tamping refractory material on all sides but not at the ends about a pattern of the same shape, 110 as the passage to be formed, and which is, made at least partly of a pliable, readily, meltable, non-metallic solid, which is sufficiently hard and strong to resist distortion 115 under the proper tamping pressure, and then melting such material by the application of heat, as claimed in the parent, application.

What I claim is:

1. The method of making the refractory structure of an electric furnace or the like, having a passage of channel, which comprises tamping refractory material about a templet of the same shape as the passage to be formed, and consisting of a metallic 120 outer part temporarily reinforced with a filling so that such templet is sufficiently 125 hard and strong to resist collapse under tamping pressure, and then eliminating the filling material. 130

2. The method of making the refractory structure of an electric furnace or the like having a passage therein, which comprises ramming refractory material about a templet of the same shape as the passage to be formed, consisting of a metallic outer part and an inner readily meltable filling which supports the outer part under tamping pressure, and then melting out the filling material. 10
3. The method of making the refractory structure of an electric furnace or the like having a passage or channel therein, which comprises tamping refractory material about a hollow templet of the same shape as the passage to be formed, having an interior filling, and then removing the filling from the templet. 15
4. The method of making the refractory structure of an electric furnace or the like having a passage or channel therein, which comprises ramming refractory material about a templet of the same shape as the passage to be formed, having an interior filling of readily meltable material, and then eliminating the filling by melting. 20
5. The method of making the refractory structure of an electric furnace or the like having a passage or channel therein, which comprises ramming refractory material about a templet of the same shape as the passage to be formed, comprising an outer comparatively thin metal tube with an interior filling, and then removing the filling. 25
6. The method of making the refractory structure of an electric furnace or the like having a passage or channel therein, which comprises ramming refractory material about a templet of the same shape as the passage to be formed, having within its periphery or circumference a body of non-metallic material, which at ordinary temperatures is sufficiently hard and strong to resist collapse under tamping pressure, but which melts at a low temperature, and then applying heat to the structure for eliminating such non-metallic material. 30
7. The method of making the refractory structure of an electric furnace or the like having a passage or channel therein, which comprises tamping refractory material about a templet of the same shape as the passage to be formed, consisting of an outer part open at at least one end and an inner body of filling material adapted to be run out of the open end of the templet, and then running the interior filling out of the templet. 35
8. A templet for the manufacture of electric induction furnaces and the like, comprising a hollow body having an interior filling of readily meltable material. 40
9. A templet for the manufacture of electric induction furnaces and the like, having within its cross-section a body of wax. 45
10. A templet for the purpose described, consisting of an outer part open at at least one end, and an interior filling. 50
11. A templet for the purpose described, comprising a metallic outer part and a non-metallic interior filling. 70
12. A templet for the purpose described, comprising a metallic tube. 75
13. A templet for the purpose described, comprising a metallic tube, and with an interior temporary filling. 75
14. A templet for the purpose described, comprising a metallic tube, and with an interior temporary filling of wax. 80
15. The method of drying a green refractory structure, which comprises the location of a collapsible electric conductor tube within and in contact with the refractory body, and the passage of an electric current through said conductor tube, whereby, on the heating of such tube, for drying the refractory structure, the lateral pressure on the latter is minimized. 85
16. A templet for the purpose described constructed in the form of a tube with an open end, and a filling adapted to be run out of such open end. 90
17. A templet for the purpose described constructed in the form of a tube with an open end, and a filling adapted to be run out of such open end, such filling consisting of a waxy substance. 95
18. The method of drying a green refractory structure, which comprises the location of a temporarily filled collapsible electric conductor within the refractory body, and the induction of current in said conductor for eliminating the filling of such conductor and thereby permitting the inward expansion of the latter to relieve pressure on the refractory walls due to the heating effect. 100
19. The method of making the refractory structure of an electric furnace or the like having a passage therein, which comprises ramming refractory material about a conductor tube having an interior filling of lower melting point than the tube, and then eliminating the filling by melting. 110
20. A templet for the purpose described, consisting of a conductor tube having a temporary, low melting point core. 115
21. The method of making a refractory structure, which comprises the location of a conductor body filled with a readily eliminable filling, within and in contact with the refractory body, the elimination of the filling, and the passage of an electric current through said conductor body for drying the refractory material without injurious pressure thereon. 120
22. The method of making the refractory structure of an electric furnace, which comprises the positioning of a conductor tube temporarily filled with wax, within and in 125
- 130

contact with the refractory body while the latter is green, and the induction of current in said tube to eliminate the wax and dry the refractory material.

5. 23. The method of making the refractory structure of an electric furnace or the like having a passage therein which comprises ramming refractory material about a hollow conductor having an interior filling, of 10 lower melting point than the conductor, and then eliminating the filling by melting while leaving the conductor in the passage.

24. A templet, for the purpose described, consisting of a hollow conductor having a 15 temporary low melting point core.

25. The method which comprises forming the refractory structure of an electric furnace or the like, having a passage therein, by ramming refractory material about a metal 20 conductor of electricity having an interior filling of lower melting point than the conductor body, eliminating the filling by melt-

ing, and then utilizing the remaining hollow conductor body in the operation of the furnace to create an electrical circuit through 25 the passage.

26. The method which consists in making the refractory structure of an electric furnace or the like by tamping operations, involving the tamping of refractory material about a hollow, metallic conductor of electricity, having an interior filling of lower melting point than the conductor body, then eliminating the filling by melting, while leaving the conductor body in situ in the 35 refractory structure, drying the walls of the passage in which the conductor body is located, and utilizing the conductor body for the conduction of an electric current through the passage.

40 In witness whereof, I have hereunto set my hand, on the 3rd day of September, 1919.

WALTER R. CLARK.
